(57) **CLAIM**

The ornamental design for a blender jar as shown and described.

DESCRIPTION

FIG. 1 is a front elevational view of the blender jar;
FIG. 2 is a back elevational view of the blender jar;
FIG. 3 is an enlarged top view of the blender jar;
FIG. 4 is an enlarged bottom view of the blender jar;
FIG. 5 is a front perspective view of the jar, with its cap offset by 180° to its position in FIG. 1;
FIG. 6 is a front elevational view of a second embodiment of the blender jar;
FIG. 7 is a back elevational view of the second embodiment of the blender jar;
FIG. 8 is an enlarged top view of the second embodiment of the blender jar;
FIG. 9 is an enlarged bottom view of the second embodiment of the blender jar;
FIG. 10 is a front perspective view of the second embodiment of the jar, with its cap offset by 180° to its position in FIG. 6;
FIG. 11 is a front elevational view of a third embodiment of the blender jar;
FIG. 12 is a back elevational view of the third embodiment of the blender jar;
FIG. 13 is an enlarged top view of the third embodiment of the blender jar;
FIG. 14 is an enlarged bottom view of the third embodiment of the blender jar;
FIG. 15 is a front perspective view of the third embodiment of the jar, with its cap offset by 180° to its position in FIG. 11;
FIG. 16 is a front elevational view of a fourth embodiment of the blender jar;
FIG. 17 is a back elevational view of the fourth embodiment of the blender jar;
FIG. 18 is an enlarged top view of the fourth embodiment of the blender jar;
FIG. 19 is an enlarged bottom view of the fourth embodiment of the blender jar; and,
FIG. 20 is a front perspective view of the fourth embodiment of the jar, with its cap offset by 180° to its position in FIG. 16.
